FUSE PLUG

Frank J. McHugh, Chicago, Ill., assignor, by
mesne assignments, to Fred R. Tuerk, Chicago,
Ill.

Application June 30, 1933, Serial No. 678,404
Renewed September 24, 1936

5 Claims. (Cl. 200—113)

My invention relates in general to protective devices for electrical circuits and has more particular reference to safety breakers or cutout devices for interrupting the circuit when the same becomes overloaded.

An important object of the invention is to provide a circuit breaker of the type having a current-carrying conductor, which, when overload conditions are set up, is adapted to rupture and open the protected circuit.

My present invention contemplates the provision of a circuit interrupter in which the current-carrying conductor may be replaced in position to render the device again effective for further use in a circuit after the conductor means has been ruptured in interrupting an overloaded circuit.

Another important object is to provide a device of the character described in a form adapted for insertion in the ordinary commercial power circuits.

Another important object is to utilize mercury or similar fluid current-carrying medium as the rupturable element of the cutout device, the device being arranged to normally receive the fluid current-conducting medium in position to complete the electrical circuit with which the device is associated and the medium being arranged for expulsion from the circuit-making position when overload conditions prevail in the circuit and being readily returnable to circuit-completing position by a simple movement imparted to the device.

Another object is to provide a circuit breaker of the character mentioned, in which the circuit-making medium may not return to circuit-completing position unless and until the device is manipulated for this purpose.

Another important object is to provide a cutout device of the character described having a relatively restricted channel, in which the circuit-making medium extends when in circuit-completing position, and from which the medium may be expelled in order to interrupt the circuit, the device being arranged to confine arcing in said restricted channel.

Another important object is to provide a simple and substantial device of the character mentioned which may be used an indefinite number of times without being replaced.

Another important object resides in the simplicity and construction of the cutout devices, the same being inexpensive and easily manufactured, yet having rugged and reliable operating characteristics.

Another object is to utilize the blowout effect of mercury in a capillary channel as an overload circuit breaker.

Another object is to utilize surface tension of a fluid, such as mercury, to hold the conducting medium in operative circuit-making position until overload conditions prevail and out of operative position after the fuse has been blown.

Another object is to provide a channel having a restricted arcing portion and an enlarged blowout receiving channel interconnected by a tapering channel portion whereby to normally prevent the blowout medium from returning to operative position in the restricted channel portion after being blown into the enlarged portion.

Another object is to utilize the natural adhesive effect of mercury on certain metals to help hold the mercury in position.

Another object is to provide a device of the character described having means to indicate whether the circuit breaker is in operative or inoperative condition.

Another object resides in providing a novel sight indicator for the device.

Another object is to provide an outlet plug having a built-in overload circuit breaker.

Numerous other objects and advantages of the invention will be apparent from the following description, which, taken in connection with the accompanying drawings, discloses preferred embodiments of the invention.

Referring to the drawings:

Figure 1 is a side elevation of a preferred form of renewable circuit breaker embodying my present invention;

Figures 2 and 3 are sectional views taken substantially along the lines 2—2 and 3—3 respectively in Figure 1;

Figure 4 is a longitudinal section illustrating a modified construction embodying my present invention;

Figure 5 illustrates the manner of manipulating the cutout device in order to replace the current-carrying medium in operative position after the same has been expelled in opening the circuit in response to overload conditions;

Figure 6 shows a preferred form of sealing means for the chamber of the breaker;

Figure 7 is a sectional view showing a cartridge type breaker embodying my present invention;

Figure 8 is a sectional view showing an outlet socket plug having incorporated therein a breaker embodying my invention; and

ures 10 and 9 respectively and showing an outlet plug embodying my present invention.

To illustrate my invention, I have shown on the drawings, in Figures 1-5, a circuit breaker 5 of the character commonly known as a blowout fuse, and, although my invention is not necessarily restricted to any particular embodiment, I have shown a plug form especially well adapted for use in fuse receptacles of the character commonly used in commercial power circuits.

The invention, however, is adapted to other forms, more particularly, as shown in Figures 7-10, the invention may be incorporated in the so-called "cartridge" type fuse, in power outlet sockets, and in outlet plugs. In any event, the invention involves the utilization of a restricted channel into which a quantity of a suitable current-carrying medium, such as mercury, may enter and be normally retained in position 10 to form an operative current carrying path between spaced terminals, the mercury being ejected from operative position when overload conditions prevail to interrupt the current-carrying circuit and being returnable to operative 20 position after expulsion in response to the application of external forces to the device.

The circuit interrupter or fuse, shown in Figures 1-5, comprises a body 11 of any suitable insulating material, preferably porcelain and 30 preferably monolithic, although the body may be formed in interconnected sections if desired. The body is preferably of general cylindrical shape and may, if desired, be formed at one end with an enlarged portion 13, the surfaces of 35 which are preferably roughened or knurled to provide a grip for the manipulation of the device including the insertion thereof in a fuse socket. Toward the opposite end of the body, the same is formed to receive a preferably threaded conductor 17, which, as shown in the drawings, comprises a sheet metal shell by means of which the device may be electrically and mechanically secured in a threaded fuse socket.

The body 11 is also provided with one or more channels preferably extending longitudinally of 45 the body and containing a quantity of a suitable current-carrying medium, such as mercury. The opposite ends of the channels preferably open at the opposite ends of the body and are hermetically sealed to prevent the mercury from oxidizing. In the form shown in Figures 1, 2, and 3, the single channel is concentric with the axis of 50 the body and comprises an enlarged portion 19 at one end, a restricted portion 21 at the other end, and an intermediate portion 23 of tapering form, which interconnects the enlarged and restricted channel portions.

The channel portions may be formed in any suitable manner as by coring or by boring the 60 enlarged and intermediate portions at one end of the body while the restricted channel portion 21 is bored from the other end. The enlarged channel portion 19 also preferably opens at the end of the body which is provided with the gripping portion 13, the end face of the body being 65 preferably counter-sunk as at 25. The restricted channel portion 21 also preferably opens at the end of the body opposite from the enlarged gripping portion 13.

The body 11 is provided with an enlarged socket 70 27 opposite the open end of the restricted channel 21 and a plug 29 of any suitable current-carrying material is seated in the socket 27 with its inner face closing the open end of 75 the restricted channel portion 21, the plug 28

being secured in the socket 27 by means of a suitable cementing material 31, or the plug may be threaded or otherwise mechanically secured in place in the socket.

The sides of the restricted channel 21 are also 5 preferably enlarged slightly as at 33 adjacent the face of the plug which closes the open end of the channel, or the plug itself may be formed with an opening in its face opposite the end of the channel in order to form a better contact 10 with the current-carrying medium.

The plug 29 also has an outer surface 35, which projects slightly beyond the end of the body 11 in order to form a central terminal whereby contact may be made with a terminal of the socket 15 in which the device is secured. It will be noted that this construction exposes a portion of the plug 29 in the channel 21. A second contact member or terminal 37 is exposed in the channel in spaced relationship with the exposed portions 20 of the plug 29. This second terminal is preferably arranged in the body 11 with its inner face exposed in the channel preferably at the tapering portion 23, the outer end of the terminal 37 forming contact with the conductor 17 25 by means of which an electrical connection may be formed between the terminal 37 and a terminal of the fuse-supporting socket, in which the device is adapted for insertion.

A quantity of mercury or other suitable current-conducting fluid 39 is enclosed in the channel, the quantity of fluid being sufficient to fill the restricted channel 21 and enter the enlargements 33 in order to form a current-conducting path between the surfaces of the terminals 29 35 and 37, which are exposed in the channel. The fluid-carrying medium may be inserted in the channel through the open end of the enlarged channel portion 19 which may then be sealed in any suitable manner as by the plug 41 cemented 40 in place in a socket 43 formed in the bottom of the countersunk portion 25 at the open end of the enlarged channel portion 19.

I prefer to use mercury as the fluid-carrying medium for electrically bridging the space between the terminals 29 and 37 in the channel and to form the terminals 29 and 37 of copper or a copper alloy with which the mercury may form a relatively weak bond sufficient to hold it in place after being forced into the restricted channel 21 between the terminals. The mercury also has a natural surface tension which will assist in holding the position illustrated in Figure 2 of the drawings. The restricted channel portion 21, however, is preferably of a size which will normally prevent the mercury from flowing into the channel, the natural tension of the mercury tending to prevent the same from flowing into the restricted channel. The tendency of the mercury to refrain from entering the channel 21 may, however, be overcome by shaking the device in the manner illustrated in Figure 5 of the drawings. By so shaking the device, the mercury may be caused to flow from the enlarged channel portion 19 into the restricted 60 portion, that is to say, into operative position forming an electrical connection between the terminals 29 and 37. When the mercury has been so arranged in operative position, its natural surface tension, together with its tendency to 70 form a bond with the terminals, will normally prevent the mercury from flowing out of the restricted channel and into the enlarged channel. The device may then be arranged in a fuse holder by simply screwing the threaded portion 17 into 75

the fuse-holding socket. When an overload occurs, the mercury will become heated and will be expelled from the restricted channel portion 21 into the enlarged portion 19, thus breaking the electrical connection between the terminals 29 and 31 and interrupting the circuit in which the device is mounted. The mercury after such expulsion will not ordinarily return to operative position in the restricted channel portion 21 but can be easily repositioned for operation by removing the device from the fuse socket and by applying external forces as by shaking the device in the manner heretofore described and illustrated in Figure 5 of the drawings. The device can thus be used more or less indefinitely without wearing out.

I prefer to form the sealing plug 41 of transparent material to form a window through which the position of the mercury in the channel may be observed from outside. The window may be formed as a flat disk of glass, mica or other suitable material cemented in place to hermetically seal the fluid medium in the channel but I prefer to form the window as an open ended shell 45, as shown in Figure 6. The open end of the shell is sealed in communication with the channel 19 with the dome of the shell protruding out of the socket 43. The shell is also necked in between its open end and the top of the dome so that when the mercury is expelled from circuit-making position in the channel, it will be forced into the dome of the shell and held there, in full view, by the action of the restricted neck in conjunction with the surface tension of the mercury. The position of the mercury can thus be determined simply by inspection and the mercury can be ejected from the dome and returned to operative position in the channel portion 21 simply by shaking the device.

By hermetically sealing the mercury in the channel, it is prevented from oxidizing and thus rendering the fuse inefficient. Slight oxidation may be caused by the oxygen in the air originally trapped in the channel but this will be quickly eliminated without any deleterious effect in the fuse after which the atmosphere within the channel will be mainly inert.

In Figure 4 of the drawings, the body 11 is provided with a plurality of channels 20, each having an enlarged portion 19, a restricted portion 21, and an intermediate tapering portion 23, the open ends of the restricted portions 21 are slightly enlarged as at 33 and closed by means of the plug 29 and each channel is provided with a preferably radially extending terminal which is exposed at the tapering portion and electrically connected with the conductor member 17, each channel having a body of fluid conducting medium 39 adapted to fill the restricted channel portion and form a connection between the terminals 29 and 31. The open ends of the enlarged channel portions are sealed by means of the members 41. The device operates in a fashion similar to that having the single channel 20 but provides a circuit breaker of higher current-carrying capacity.

The capacity of the device may also be varied to a certain extent by changing the size of the channel 21, but for heavy duty breakers, I prefer to use a plurality of channels connected in parallel in the circuit.

In Figure 7 of the drawings, I have shown the invention as embodied in a so-called cartridge type fuse. In this form, the body 11 is preferably cylindrical and the channel 20 is formed

longitudinally of the cylindrical body with the enlarged portion 19 opening at one end and the restricted portion 21 at the other end of the body, the restricted portion opening into an enlarged socket 27 in which is mounted the plug 29, the plug being held in place by means of the cement 31. The restricted channel 21 also is or may be slightly enlarged as at 33 in the vicinity of the surface of the plug, or the surface of the plug may be hollowed out, as shown in dotted lines at 34, in order to improve the contact between the face of the plug and the mercury column in the channel.

The electrode, corresponding to the electrode 31 of the form shown in Figures 1 through 5 of the drawings, has a contacting portion mounted at the tapering portion 23 of the channel and has an arm 47 extending along a side of the enlarged channel portion 19 to the outer end of said channel portion, the opposite ends of the body 11 are provided with ferrules 49 which are secured to the body as by means of the cement 51, or the sides of the body may be threaded, as at 52, to receive the ferrules. The threaded connection is preferred where the body 11 is formed of fibre, while cemented ferrules may be used where the body is formed of porcelain. The ferrules are also preferably soldered to the plug 29 and to the end of the arm 47. The ferrules also may be provided with knife blades 53 if it is desired to mount the fuse in a holder having knife blade supports. The operation and manipulation of the fuse is similar to that heretofore described in connection with the fuse illustrated in Figures 1 through 6.

In Figure 8, I have illustrated an outlet device 55 adapted to receive the prongs 57 of an outlet plug 59 and connect the prongs in the electrical circuit in which the outlet device is mounted.

The outlet device incorporates a circuit breaker embodying my present invention and comprises a generally cylindrical body similar in form to the body 11 of the device illustrated in Figures 1 through 6. The body is provided with the breaker channel having an enlarged portion 19, the tapering portion 23 and a restricted portion 21, the restricted portion being sealed at one end of the device by means of the terminal plug 29 held in place by means of the cement 31. The open end of the breaker channel 20 is sealed in any suitable or convenient manner as by means of the sealing disk 41. The body of the device is formed with a pair of channels 61 on opposite sides of the breaker channel 20. One of these channels communicates with the channel containing the terminal 37, while the other channel communicates with the side of the body behind the threaded shell 17 and each channel 61 contains a spring contact 63 in position to engage and form an electrical connection with the prongs 57 of the plug 59 when the same are inserted in the channels 61. One of the spring contacts 63 extends through its channel and forms an electrical connection with the shell 17, while the other spring contact forms an electrical contact with the terminal 37. The terminal 37 in the device shown in Figure 8 does not engage the shell 17 as is the case in the forms shown in Figures 1 through 6 but the outer end of the terminal is removed and the space in the channel between the shell 17 and the terminal is sealed with any suitable insulating compound 65 after the terminal 37 and its associated spring terminal 63 have been assembled.

The space in the channel through which the

other spring terminal 63 extends into engagement with the shell 17 is also preferably sealed with a suitable insulating compound in order to hold said spring terminal in place after insertion. When the circuit-making fluid 39 is in position as shown in Figure 8, forming a circuit between the plug 29 and the terminal 37, one of the prongs 57 of the plug will be electrically connected through the shell 17, while the other prong 10 will be connected through the terminal 37, the mercury column 39 and the terminal plug 29. The operation of the circuit breaker is similar to that heretofore described in connection with the device shown in Figures 1 through 6.

In Figures 9 and 10, I have shown a circuit breaker embodying my present invention as incorporated directly in a pronged plug adapted for insertion in an outlet socket.

The device shown in Figures 9 and 10 comprises a body 71 of any suitable insulating material provided with the channel 20 having an enlarged portion 19, a restricted portion 21, and an intermediate tapering portion 23, the open end of the restricted channel portion 21 being closed by the terminal plug 29 which is held in place in the socket 27 as by means of the cement 36, the open end of the enlarged channel portion 19 being sealed in any suitable manner as by the sealing member 41. The body 71 has a channel 73 formed therethrough to receive a cable, one wire of which is electrically connected to the prong 77 which is secured to the body 71 in any suitable manner. The body also carries a prong 79 secured thereto in parallel spaced relationship with respect to the prong 77 and the prong 79 is connected as by the contacting screw 81 with the terminal 37, the outer end of which is relieved as in the form of the device shown in Figure 8 in order to permit a sealing compound 65 to be arranged in the channel containing the terminal 37 in order to protect the terminal from exposure on the side of the body 71. The inner face of the terminal 37 is exposed in the circuit breaker channel 20 preferably at the tapering portion 23. The other conductor of the cable 75 is electrically connected to the terminal plug 29.

It is thought that the invention and numerous of its attendant advantages will be understood from the foregoing description and it is obvious that numerous changes may be made in the form, construction, and arrangement of the several parts without departing from the spirit or scope of my invention or sacrificing any of its attendant advantages; the forms herein described being preferred embodiments for the purpose of illustrating my invention.

Having thus described my invention, what I claim as new and desire to secure by Letters Patent is as follows:

1. A circuit interrupter comprising a body of insulating material having a channel including a restricted channel portion, a pair of spaced electrodes exposed in said restricted channel portion, a fluid electrical conducting medium in said channel and adapted to enter the restricted channel portion and form a conducting path between the electrodes, contact-making prongs on said body and electrically connected with said

electrodes and adapted for insertion in the slots of an outlet socket whereby to provide means for electrically connecting the electrodes with the conductors of the socket.

2. A circuit interrupter comprising a body of insulating material having a channel including a restricted channel portion, a pair of spaced electrodes exposed in said restricted channel portion, a fluid electrical conducting medium in said channel and adapted to enter the restricted channel portion and form a conducting path between the electrodes, said body being formed to receive the prongs of an outlet plug, contactors to engage the prongs, means to electrically connect at least one of the contactors and one of said electrodes in an external circuit, and means to electrically connect the other contactor with the other electrode.

3. A circuit interrupter comprising a body of insulating material having a channel including a restricted channel portion, a pair of spaced electrodes exposed in said restricted channel portion, a fluid electrical conducting medium in said channel and adapted to enter the restricted channel portion and form a conducting path between the electrodes, and contact-making elements on said body and adapted for connection in an external electrical circuit, means electrically connecting at least one of said contact-making elements with one of said electrodes, a channel in said body for receiving a cable having a plurality of conductors, means to electrically connect one of the conductors of said cable with the other of said contact-making elements, and means to connect the other conductor of said cable with the other electrode.

4. A circuit interrupter comprising a body of insulating material having a channel extending from end to end of said body, said channel being restricted at one end and enlarged at the other, means forming a translucent window closing the enlarged end of said channel, an end electrode closing the restricted end of the channel, said electrode being exposed on one side in said channel and on the other side exposed outwardly of the end of said body, an intermediate electrode exposed in said channel substantially at the junction of the restricted and enlarged channel portions, a contact-making element carried on and exposed outwardly of said body, and means electrically connecting the intermediate electrode with said contact-making element.

5. A circuit interrupter comprising a body of insulating material formed with a cavity providing a chamber within said body, said body being formed with restricted ducts communicating with said cavity and extending to an opening on the surface of said body, terminal means closing the ends of said ducts and exposed therein, electrode means communicating with each duct at its junction with said cavity, a fluid electrical conducting medium in said cavity and adapted to enter the restricted ducts at their points of communication with said cavity, and a contact-making element on said body and exposed outwardly thereof and electrically connected with said electrode means.

FRANK J. MCHUGH.
